HOLDER FOR RIBBON TYPE RAZOR BLADE

Maxym Olijnyk, New York, N. Y.

Application September 13, 1954, Serial No. 455,461

7 Claims. (Cl. 30—40)

The invention relates to a novel holder construction safety razor assembly with a ribbon blade. Whereas most of the conventional safety razors in use at the present time have single or double edged interchangeable blades, such blades have to be changed more or less frequently, the blades have to be stored separate from the safety razor, and the method of changing blades is not always convenient, nor positively safe. The invention herein referred to has as its object to overcome the inconveniences of many safety razors now in general use by providing a pair of rollers for supporting the ribbon blade, the ribbon blade being attached to the rollers and wound up one of the rollers and a split spring metal ring which engages the periphery of the ribbon blade and helps to hold the same in place in the razor, the assembly being in accordance with the following relationship: a safety razor blade consisting of an elongated thin and narrow ribbon of hard metal with at least one sharp edge is attached to the novel holding device of the present invention, said ribbon being wound on a roller; the roller comprises a cartridge with the ribbon blade wound on same and held securely in place, the length of the ribbon blade being sufficient to provide for long use with a fresh sharp edge available at all times by rotating a roller.

The razor blade holder consists of a frame with two apertures for the rollers, two slots at right angles to the rollers for stretching the ribbon blade thereon, and one rectangular aperture in the block located above the roller apertures for shaving waste material, and four slots on top of the rectangular aperture to lead shaving waste material from the blade into the rectangular aperture.

The elongated ribbon blade wound around a roller is inserted into a roller aperture of the holder and the free end of the ribbon blade is drawn out through the side slot in the holder at a right angle to the roller, and thus drawn, the ribbon blade goes around the top of the holder, into a slot on the opposite side of the holder and is fastened to the end of the second, empty roller. The elongated metal ribbon blade drawn around the head of the holder is made secure to the holder by means of a metal frame clamp whose leg ends are flexible and provided with knobs at their ends which, when the frame clamp is completely inserted, become securely set in corresponding depressions in the holder. The metal ribbon blade is held securely in position passing within side channels in the holder and in a groove of the head of the holder, and a rib in the frame clamp to prevent side slipping. The metal ribbon blade is prevented from unwinding off its roller by means of a brake washer pressing against the flanges of the rollers, the brake washer held by a spring and sliding bolt, a further safeguard against the unwinding of the ribbon blade is provided by a split spring ring encasing the periphery of the roller.

The handle of the safety razor blade holder is constructed of two parts, hinged to the holder and folding together to enclose the holder when the razor is not in use, thus forming a box shielding the blade and holder;

2

the handle is unfolded for use of the razor and its two parts are locked together by a concavity in one part, and a corresponding rib in the other part, as well as by an additional slip bolt.

With the above mentioned, and other objects in view, as will become hereinafter apparent, the invention consists in general of certain novel details of construction and of combinations of parts hereinafter fully described, illustrated in the accompanying drawings, and particularly claimed.

In particular, the following figures represent:

Fig. 1 is a front view of the safety razor unit with the box handle in unfolded position.

Fig. 2 is a side view of the safety razor unit with the box handle in unfolded position (section on line 2—2), see Fig. 1.

Fig. 3 is a side view of the safety razor unit with handle folded to form box (section on line 3—3), see Fig. 1.

Fig. 4 is a side view of the rollers with ribbon blade unlocked (section on line 4—4), see Fig. 5.

Fig. 5 is a front view of the rollers with ribbon blade attached to rollers, unwinding from one, and winding upon the other roller.

Fig. 6 is a view of the safety razor metal ribbon blade, section thereof.

Fig. 7 is a view of the head of the razor blade holder with one sectioned frame leg, and the ribbon blade in a side holder channel.

Fig. 8 is a front view of the frame clamp.

Fig. 9 is a side view of the frame clamp.

Fig. 10 is an enlarged front view of lock and spring securing the ribbon blade to the head of the holder.

In the construction of the safety razor with ribbon blade two rollers 1 and 2 (Fig. 1) are provided, on one of which the flat ribbon blade 3 is wound, said ribbon blade having at least one sharpened edge 4 (Fig. 6). Part 5 of the flat ribbon is blunt and somewhat wider than the sharpened portions of the ribbon blade which is attached to the rollers by means of additional lead ribbons 6 and 7 (Figs. 4 and 5). The ends of the lead ribbon are attached to the rollers by means of slot 8 and pin 9 (Figs. 2, 4, 5).

The free ends of the lead, permanently attached ribbons are T-shaped (Fig. 4). The ends of the ribbon blade are provided with appropriate apertures 10 through which they are locked onto the T-shaped ends of the lead ribbons 6 and 7.

As shown in Fig. 4 lead ribbon 7 for mounting ribbon blade 3 to the roller is provided with projecting tongue 51 which is narrower at the neck of said tongue than the width of the slot 10 to permit the ribbon 3 and lead 7 to be flat in relation to each other after the tongue and slot are interengaged. Tongue 51 terminates in a widened end portion 52 which is wider than the width of slot 10 and shorter in width than the length of slot 10 to permit portion 52 to be inserted through slot 10. Lead ribbon 6 is similarly constructed with respect to its through engagement with the other end of razor ribbon 3. At opposite attached ends, lead ribbons 6 and 7 respectively lie in flat face to face relationship to the corresponding ends of the razor ribbon 3.

As shown in Fig. 5 the insert of ribbon 7 is passed through the opening of the open spring ring 11 and is attached to the roller by passing the terminal end through slot 8 so as to be held therein by pin 9. The sectional view of the roller which is shown in Fig. 4 with the ribbon blade in unlocked position provides a clear illustration of the attachment action of the pin.

The ribbon blade wound on a roller is held in place by means of open spring ring 11 (Figs. 1, 2, 4, 5). The roller cartridge with a ribbon blade and spring ring sur-

rounding the latter is inserted into the round opening of the holder 12 in such manner that the roller flanges 13 rest in the appropriate counterbore of the opening (Figs. 1, 2).

From the roller 1 the ribbon blade is drawn through side slot 14 in the holder, extending up along holder side channel 15, encircling the head portion of the holder, and then down side channel 16 through side slot 17, and is locked onto roller 2 by means of short blunt ribbon 7 (Figs. 1, 5, 7).

The frame clamp 18 (Figs. 1, 2, 8, 9) holds the ribbon blade to the head of the holder, and the legs 19 of the clamp 18 cover the ribbon blade loosely in side channels 15 and 16 (Figs. 1, 7), and keeps the ribbon blade in place.

The legs 19 of the frame clamp 18 have two knobs 20 which, when set in the depressions of the holder, keep the frame clamp 18 firmly in place; the ends of legs 19 are flexible.

On U-shaped frame clamp 18 there is also rib 21 which dips from a center bar connecting the legs 19 into an appropriate groove on the head of the holder, bends the ribbon blade slightly, and keeps said ribbon blade more firmly in place (Fig. 2 and Fig. 3 show the rib 21 bending the ribbon blade and Fig. 8 shows the details of the U-clamp).

Between the roller openings there is an opening or counterbore 22 (Fig. 3) in which there is provided spring 23 and sliding bolt 24 with brake washer 25 on the end of the bolt (Figs. 1, 3). The brake washer 25 is mounted on the bolt loosely and is free to slide and turn on its axis. The spring and bolt press the brake washer 25 to the flanges of the rollers, and therefore pressing action of the washer 25 permits it to exercise its braking function to prevent the rollers from unwinding the ribbon blade.

One segment of the washer 25 is cut off, and on the opposite side there is a small depression 21a into which pin 26 enters (Figs. 1, 3), the pin keeping the washer from turning. In this manner when pin 26 enters the depression in the washer 25 the brake action of the washer 25 is facilitated.

On the lower portion of the holder are two ribs 27 (Figs. 1, 2, 3) to which the handle parts are attached by rods 28. The handle consists of two parts 29 and 30, hinged on the rods, and when the handles are folded (Fig. 3) they form a box for the holder. Handle parts 29 and 30 are provided with bent edges 31 which lock on groove 32 of the clamp (Figs. 1, 2, 3, 8, 9).

When the handle parts are in an unfolded position, a firm handle unit is provided by their locking through slip bolt 33 (Figs. 1, 2). There are four slots 34 in the head of the holder and through these slots waste passes into chamber 35. Part of the head portion of the holder alongside slots 34 is provided with a conventional comb 36 (Figs. 1, 2, 7).

Through the entire head portion of the holder there is an opening 37, into which a lock is inserted (Figs. 2 and 3). The lock consists of two metal rods 38 and a spring 39 mounted on the narrowed ends of the rods. The outer ends of the rods 38 are conical shaped and under tension of spring 39 the ends of rods 38 enter into openings 40 of the ribbon blade (Fig. 6), and finally rest in depressions 41 of the frame clamp (Figs. 1, 8, 9) thus securing the sharp edge of the ribbon blade 4 (Fig. 6) on the head portions of the holder, and providing an additional safeguard against the ribbon blade rolling back in the event of its breaking.

After metal ribbon blade 3 is used up to the end, and it is necessary to replace it with a new ribbon blade cartridge, bolt 24 is pushed in the direction of washer 25 disconnecting the washer with pin 26. Washer 25 is turned on bolt 24 so that flange 13 of the roller becomes free. In this position of the washer the clamp is pulled away, metal ribbon blade 3 is unlock from blunt short ribbon of empty roller and the roller with the used rib-

bon blade encircled by safety ring is pushed out from its hole in the holder. A new roller cartridge is inserted in its place and the end of the new ribbon blade is locked onto the blunt ribbon of the empty roller, washer 25 is turned back to its former position and clamp 18 set in place. The safety razor is, after this replacement operation, again ready for use for a long time.

While there is herein shown and described the preferred embodiment of the invention, it is nevertheless to be understood that minor changes may be made therein without departing from the main idea and scope of the invention as claimed.

What is claimed as new is:

1. A ribbon type blade safety razor comprising a blade assembly including an elongated flat ribbon of hard metal sharpened along at least one edge thereof, a holder for said ribbon comprising a pair of rollers for supporting said ribbon blade, said ribbon blade attached to said rollers and wound on one of said rollers, an open spring metal ring encasing the periphery of the ribbon of hard metal wound on said rollers and helping to hold said ribbon in place, said rollers provided with flanges and braking means interposed between said rollers and said flanges to exert a frictional braking drag thereon and thereby hold said ribbon in place.

2. A ribbon type blade safety razor comprising a safety razor holder assembly for an elongated flat ribbon of hard metal sharpened along at least one edge thereof comprising a pair of rollers for supporting said ribbon blade, said ribbon blade attached to said rollers and wound on one of said rollers, said rollers provided with flanges, and a brake washer interposed between said rollers and engaging said flanges to exert a frictional drag thereon.

3. A ribbon type blade safety razor comprising a safety razor blade holder assembly as recited in claim 2 in which said washer is provided with a cut-off segment on one side thereof and there is a depression in a side of said washer which is opposite said cut-off segment, and a pin positioned in said depression to prevent said washer from turning.

4. A ribbon type blade safety razor comprising a holder for an elongated flat ribbon type razor blade comprising rollers for holding said ribbon blade and means for guiding said ribbon blade in a path extending between said rollers through the head portion of the holder, the head portion of said holder provided with an opening and a lock inserted into the same, said lock comprising two metal rods and a spring securing the sharpened edge of said ribbon blade to the head of said holder and providing a safety guard against said ribbon blade rolling back in the event of said blade breaking.

5. A ribbon type blade safety razor comprising a blade assembly, a holder for an elongated flat ribbon type razor blade, said holder having a supporting structure including mounting counter bores therein, a head comprising rollers constituted by flanged spools mounted within said counter bores, a channel in each side of said holder for guiding said ribbon blade in a path extending between said rollers through the head portion of said holder and a U-shaped clamp having a center bar for retaining said ribbon blade in place, the legs of said clamp extending into said side channels and said center bar covering said head portion and providing a safety guard for said blade.

6. A ribbon type blade safety razor comprising a blade assembly, a holder having hinge means at the bottom thereof adapted to hingedly support handle members, said holder having ribbon type razor blade supporting structure including mounting rollers and a channel in each side of said holder for guiding said blades between said rollers, a U-shaped clamp having a center bar for holding said blades and legs extending into said channels, said center bar having a longitudinal groove in its outer surface, a pair of handle members supported by

said hinge means, each of said handle members having a bent outer edge for locking engagement with said longitudinal groove when said handle members are pivoted in locking position enfolding said holder.

7. A ribbon type blade safety razor comprising a pair of rollers adapted to support an elongated flat razor ribbon of hard metal sharpened along at least one edge thereof, said rollers each comprising an outwardly extending flange, a pin and a lead ribbon secured to said pin, each of said lead ribbons having a free end provided with attaching means adapted to interengage with slots adjacent the ends of said ribbon blade for securing said ribbon blade to each lead ribbon, said lead ribbons lying in flat relation in attached condition with respect to said ribbon blade, said ribbon blade wound on one of said rollers and a brake washer interposed between said rollers and engaging said flange of said rollers to exert a frictional drag thereon.
